UNITED STATES PATENT OFFICE.

WESLEY F. CORNELIUS, OF WHITTIER, CALIFORNIA.

SUCKER-ROD ELEVATOR.

Application filed March 16, 1925. Serial No. 15,974.

To all whom it may concern:

Be it known that I, WESLEY F. CORNELIUS, a citizen of the United States, residing at Whittier, in the county of Los Angeles and State of California, have invented certain new and useful Improvements in Sucker-Rod Elevators, of which the following is a specification.

My invention relates to an oil well sucker rod elevator and has for its principal objects the provision of a relatively simple, practical and efficient elevator that may be readily engaged upon a sucker rod beneath one of the joints thereof, to provide readily releasable self-closing latching means for securing the elevator to the sucker rod, and further to provide a device of the character referred to that will be effective in minimizing the time and labor involved in applying the elevator to the sucker rod and likewise in releasing and disengaging the elevator from said rod.

With the foregoing and other objects in view, my invention consists in certain novel features of construction and arrangement of parts that will be hereinafter more fully described and claimed and illustrated in the accompanying drawings, in which:

Fig. 1 is a perspective view of an elevator of my improved construction and showing a section of sucker rod adjacent thereto.

Fig. 2 is an enlarged vertical section taken approximately on the line 2—2 of Fig. 1 and showing the elevator in engagement with a sucker rod.

Fig. 3 is a view looking against the under-side of the block or body of the elevator, with the under plate thereof removed.

Fig. 4 is an enlarged detail section taken on the line 4—4 of Fig. 1.

Fig. 5 is a perspective view of one of the latching jaws forming a part of my improved elevator.

Referring by numerals to the accompanying drawings, which illustrate a practical embodiment of my invention, 10 designates a metal block through the center of which is formed a vertically disposed aperture 11, of sufficient size to receive a sucker rod and the upper portion of this aperture gradually increases in diameter toward the top of the block, thereby forming a curved seat 12, upon which is adapted to rest the correspondingly curved tapered portion 13, that is formed adjacent to the end of a standard sucker rod R.

Formed in the front portion of the block 10, is a tapered mouth or opening 14, that communicates with the opening 11 and its tapered upper portion 12. This mouth or opening 14 is vertically disposed, so that when the block is moved in a horizontal direction toward the sucker rod, the latter will pass through the mouth or opening 14, until it rests in the opening 11.

Formed integral with, or fixed to the sides of block 10 are trunnions 15, upon which are journalled loops 16, that are formed on the lower ends of the legs of an elongated bail 17.

Removably secured to the under side of block 10 is a plate 18, in which is formed a slot 19 that coincides with openings 14 and 11, and formed in the under side of block 10 beneath this plate is a substantially circular groove 20, the front portion of which communicates with the opening 14 directly in front of opening 11.

Arranged for sliding movement within the side portions of this slot 20, are arcuate latching members 21, the forward ends of which are bevelled as designated by 22, and the rear ends of said members being provided with plates 23 that are adapted to be engaged by the thumb and forefinger when said latching members are actuated to release a sucker rod from the block. These plates 23, normally occupy a recess 24 that is formed in the rear position of block 10, and in order to limit the movement of said plates toward each other when they are actuated to release a sucker rod, a lug 25 is provided on the rear upper portion of plate 18 and which lug forms a stop for said plates.

Formed in the under side of block 10 and diametrically disposed with respect to the circular slot 20, is a slot 26 having widened ends 27, and occupying this slot is a flat spring or a leaf spring 28, the ends of which occupy notches 27' that are formed in the inner faces of the arcuate latch members 21. The central portion of this spring 28 bears on a lug 29 that is formed at the center of slot 26.

This spring normally exerts pressure against the arcuate members 21, to move the same forwardly through the slot 20, so that the bevelled forward ends of the latching members project into opening 19 immediately in front of the vertical opening 11, and thus when a sucker rod occupies

opening 11, the elevator block 10 is latched or secured to said sucker rod by the forward ends of the latching members.

To engage the elevator on a sucker rod, block 10 is swung toward the sucker rod so that the latter enters mouth or opening 19 and as the rod bears against the bevelled front ends 22, of the latching members 21, the resistance offered by spring 28 will be overcome so as to move the latching members rearwardly through slot 20 a sufficient distance to permit the sucker rod to pass the ends of the latching members and rest in opening 11. As soon as the rod is thus positioned in the opening 11, spring 28 forces the latching members forwardly through slot 20, so that the forward ends of said members are positioned immediately in front of the rod and thus the elevator block and rod are temporarily connected.

The elevator and the rod engaged thereby are elevated or lowered in the usual manner by the hoisting connections that lead upwardly from bail 17, and when it is desired to disconnect the elevator from the engaged sucker rod, plates 23 are engaged by the thumb and forefinger and as said plates are forced toward each other, the latching members 21 are drawn rearwardly through slot 20 a sufficient distance to permit the sucker rod to be withdrawn from opening 11 by a lateral movement of block 10 relative to said sucker rod.

Thus the time and labor necessary to connect or disconnect the elevator block and sucker rod are reduced to a minimum.

By constructing the front and rear portions of the block so that they balance each other and extending the trunnions 15 outwardly from the upper portions of the sides of the block, the latter normally occupies a horizontal position between the lower ends of bail 17 and thus it is a comparatively easy matter to move the block into and out of engagement with a sucker rod.

The tapered seat 12 at the upper end of opening 11, is purposely curved so as to fit the correspondingly curved portion of the sucker rod, and as a result of this construction the rod has a relatively large area of bearing surface on the elevator block, thereby effectually resisting strains, stresses and wear.

Thus it will be seen that I have provided an oil well sucker rod elevator that is relatively simple in structure, capable of being easily and cheaply produced, easily connected to or released from a sucker rod, and which elevator is strong and durable, and well able to withstand the rough usage to which it is ordinarily subjected.

It will be understood that minor changes in the size, form and construction of the various parts of my improved sucker rod

elevator may be made and substituted for those herein shown and described, without departing from the spirit of my invention, the scope of which is set forth in the appended claims.

I claim as my invention:

1. In a sucker rod elevator, a block provided with a vertically disposed sucker rod-receiving opening, a pair of latching members arranged for operation on said block, and a flat spring arranged so that its ends directly engage the intermediate portions of said latching members for normally forcing their forward ends into said sucker rod-receiving opening.

2. In a sucker rod elevator, a block provided with vertically disposed sucker rod-receiving opening, that is provided at its upper end with a tapered seat for a shoulder on the sucker rod, a pair of latching members arranged for operation on said block and a flat spring arranged so that its ends directly engage the intermediate portions of said latching members for normally forcing their forward ends into said sucker rod-receiving opening below said tapered seat.

3. In a sucker rod elevator, a block provided with a sucker rod-receiving opening, a pair of arcuate latching members arranged for operation on said block, a transversely arranged flat spring having its ends in direct engagement with the intermediate portions of said latching members so as to force the forward ends thereof into said sucker rod-receiving opening and integral means on the rear ends of said latching members whereby the same may be manually engaged and manipulated so as to withdraw the forward ends thereof from said sucker rod-receiving opening.

4. In a sucker rod elevator, a block provided with a sucker rod-receiving opening, a pair of arcuate latching members arranged for operation on said block, a transversely arranged flat spring having its ends bearing in notches in said latching members so as to force the forward ends thereof into said sucker rod-receiving opening, means on the rear ends of said latching members whereby the same may be manually engaged and manipulated so as to withdraw the forward ends thereof from said sucker rod-receiving opening, and a stop for limiting the rearward movement of said latching members.

5. In a sucker rod elevator, a block provided with a sucker rod-receiving opening, a pair of arcuate latching members arranged for operation on said block, a transversely arranged flat spring having its ends bearing in notches in said latching members so as to force the forward ends thereof into said sucker rod-receiving opening, means on the rear ends of said latching members whereby the same may be manually engaged and manipulated so as to withdraw the forward

ends thereof from said sucker rod-receiving opening, a stop for limiting the rearward movement of said latching members, and a bail pivotally connected to the sides of said block in a plane above the center thereof.

6. In a sucker rod elevator, a block provided with a vertically disposed sucker rod opening, a pair of arcuate latching members arranged for operation on said block, a flat spring arranged in a recess in said block with its ends directly engaging the latching members for normally forcing their forward ends into the sucker rod-receiving opening and the central portion of which spring has bearing on a part of said block.

7. In a sucker rod elevator, a block pro-

vided with a vertically disposed sucker rod opening, a pair of arcuate latching members arranged for operation on said block, a flat spring arranged in a recess in said block 20 with its ends directly engaging the latching members for normally forcing their forward ends into the sucker rod-receiving opening, the central portion of which spring has bearing on a part of said block and lugs on the 25 rear portions of said latching members which lugs are adapted to be engaged by the thumb and finger of an operator's hand when said latching members are actuated to release an engaged sucker rod.

In testimony whereof I affix my signature
WESLEY F. CORNELIUS.
